FIREPROOF LEGGING

Application filed May 23, 1928. Serial No. 280,083.

My invention relates to an improved construction of fire proof legging for use in foundries and other places where the legs of workmen require protection against the action of molten and hot metal.

In connection with leggings of the kind under consideration, it has been found advisable in the first place to provide fastening devices of one kind or another to keep the legging in desired position on the leg of the user, and in the second place it has been found desirable to construct the fastening devices so that they may be quickly undone to permit the legging to be quickly removed from the leg of the user, for example where molten metal splashes under any part of the legging. I am aware that fastening devices of various kinds have been proposed heretofore, that will in one way or another facilitate quickly releasing the legging from the leg of the user, but as far as I am aware all of these fastening devices are open to a common objection, namely that in releasing the fastening devices heretofore employed, it has been necessary to grasp the legging, or a part attached to it, at some particular location on the legging to release the fastening devices. In an emergency this is not always quickly accomplished, and valuable time frequently is lost before the user finally grasps the part of the legging which must be operated to release the fastening devices. By my invention I provide an improved form of fastening devices for securing the legging in place on the leg of the user, which fastening devices, besides holding the legging snugly in desired position, are susceptible of being undone to release the legging from the leg of the user, by grasping any part of the outer edge of the legging and pulling it outwardly from the remaining part of the legging, with the result that the entire legging is at once released from the leg of the user, regardless of where the edge of the legging is grasped in attempting to remove it. A further advantage incident to my improved fastening devices is that the motion required to undo the fastening devices and free the legging, is the same motion that the user instinctively makes in an emergency,

in attempting to tear the legging from his leg, from which it will appear that with my improved fastening devices, the user need only be concerned in an emergency, with attempting to pull the legging from his leg, and need give no thought to whether any particular motion is required to undo the fastening devices or not.

By my invention I also provide special reinforcing means co-operating with the fastening devices referred to, to keep the legging in place on the leg of the user.

My invention will best be understood by reference to the accompanying drawings showing a preferred embodiment thereof in which—

Fig. 1 shows my legging in side elevation, fastened on the leg of a user,

Fig. 2 shows in inside elevation a part of the inner edge of the legging, removed from the leg of the user,

Fig. 3 shows in elevation the inner surface of the front portion of the legging removed from the leg of the user,

Fig. 4 shows in front elevation the edge portions of the legging in the relation they occupy when fastened together in use,

Fig. 5 shows in a view similar to Fig. 4 the outer edge portion of the legging in the position it assumes when free from the inner edge portion of the legging,

Fig. 6 shows in side elevation and to an enlarged scale the detail construction of the fastening devices, and

Fig. 7 is a sectional view of the parts shown in Fig. 6 taken along the line 7—7.

Similar numerals refer to similar parts throughout the several views.

As shown in Fig. 1, my legging consists of a sheet of flexible material 10 which may be of leather, asbestos or canvas, to the outer surface of the inner edge portion of which, metal fastening strips 11 and 12 are secured in any desired manner, preferably by rivets 13, adjacent the upper and lower edges of the legging. The fastening strips 11 and 12 are provided with outwardly projecting pockets 14 and 15, preferably formed by suitable dies from the body portion of the strips 11 and 12, the pockets 14 opening downwardly and the

pockets 15 opening upwardly. The outer edge of the sheet of material has supported in a hem 16, a metal reinforcing bar 17 extending nearly the entire height of the legging and preferably held securely in the position indicated by rivets or equivalent fastening devices 18, 18 extending through the bar and through the outer edge of the legging. The bar 17 is of such a length that its ends 10 extend into the pockets 14 and 15 to hold the outer edge of the legging snugly against its inner edge portion as indicated in Fig. 4.

The construction of the fastening strips 11 and 12 is the same, excepting that the pockets 15 open downwardly and the pockets 14 open upwardly, and it is necessary therefore to describe but one of these strips, for example the strip 11. As shown in Figs. 6 and 7, the pockets 14 projecting from the strip 11 are formed 20 integrally with the strip, preferably by suitable dies, and each is flat and of oval conformation where it joins the body portion of the strip 11. As indicated in Fig. 6, the end of the bar 17 is shouldered at 17^a, and continued 25 beyond the shouldered portions as indicated at 17^b, the end portion 17^b being substantially narrower than the body portion of the bar and having a rounded end as indicated. The lower end of the bar 17 is similarly formed. The 30 distance between the shoulders at the ends of the bar 17, is substantially the same as the distance between the pockets 14 and 15, and the shoulders serve to effect engagement between the ends of the bar and the pockets to the desired degree.

The rounded end portions of the bar 17 are of such length that they catch in the pockets 14 and 15 sufficiently to positively retain the legging in place on the leg of the user, and yet 40 without sufficient engagement to prevent the ready separation of the bar from the pockets when any part of the bar is pulled outwardly from the inner portion of the legging. To facilitate the ready separation of the bar from 45 the pockets, a substantial clearance is provided in each pocket in all directions around the end of the bar, as indicated in Figs. 6 and 7, and the rounded edge portions of the pockets cooperate with the rounded ends of the 50 bar, to permit the ends of the bar to slip freely from the pockets, when any part of the bar is moved outwardly in removing the legging from the leg of the user.

As shown in Fig. 5, I prefer to give the bar 55 17 a curved conformation, so that when the bar engages the fastening strips 11 and 12 as indicated in Fig. 4, the bar presses the outer edge of the legging snugly against its inner edge portion throughout the entire extent of the overlap of the outer edge portion on the inner edge portion. To facilitate this action, 60 I prefer to make the bar 17 of spring steel, or of metal having a sufficient amount of spring 65 action to bend as required in fastening the leg-

ging on the leg of the user and removing it therefrom. When the outer edge portion of the legging on the leg of the user is engaged at any point vertically and moved outwardly to substantially the position indicated in dotted lines at 17^c, the ends of the bar slip from the pockets releasing the fastening devices and in turn completely releasing the legging from the leg of the user in the manner above referred to. In putting the legging on the leg 70 of the user, the bar 17 is similarly sprung outwardly to engage its ends in the pockets 14 and 15, the particular pockets selected depending upon the size of the leg of the user, and there being a plurality of these pockets on 75 each of the strips 11 and 12 to make the legging adjustable as to size.

To maintain the fastening strips 11 and 12 at the correct distance from each other to properly engage the ends of the bar 17 as 80 described, I find it desirable to secure to the inner surface of the inner portion of the legging, a strip of stay material 19 as indicated in Fig. 2, this material being preferably 85 upholsterer's webbing, canvas or other flexible material having practically no stretch in it. The material 19 preferably extends substantially from the upper to the lower portion of the legging and has extending through it the 90 rivets 18, and is preferably stitched at its edges to the legging. With this construction, the body portion of the legging 10 may be made of soft pliable material for example 95 soft leather or asbestos, which has little stability from the standpoint of stretching, and yet the strips 11 and 12 may be positively 100 maintained a desired distance apart.

As indicated in Fig. 3, I preferably reinforce the front portion of the legging with narrow sheets 20 of stiff material, for example 105 press board, which are preferably sewed to the material of the legging 10 to lie on either side of the shin of the user, and where additional protection is desired, I 110 preferably cover these reinforcing sheets 20 with pieces of fabric 21 sewed to the legging material 10 outside of the edges of the sheets 20. The sheets 20 cooperate with the bar 17 to maintain the entire legging in desired 115 position on the leg of the user, and prevent it working into folds extending around the leg of the user, and in this way the legging as a whole is prevented from working up away from the foot and down away from the knee 120 of the user. If desired, the sheets 20 need not be stitched to the material 10 where the covering material 21 is employed.

As indicated in Figs. 1 and 3, I prefer to 125 secure to the lower edge of the front portion of the legging, a flare 22 extending over the shoe of the user, and to permit free movement of the foot, the flare is preferably of soft leather or canvas. Where the entire flare is soft and not reinforced, it readily becomes 130 displaced on the foot of the user so that it

does not properly protect the foot; to avoid this, I secure to the under portion of the toe portion of the flare a piece of stiff material 23, extending but part way from the front 5 edge of the flare to the legging proper. The reinforcing piece 23 may be of any suitable material, for example press board, and by retaining the toe portion of the flare in proper position and shape, it prevents displacement 10 of the remaining portion of the flare on the foot of the user.

While I have shown my invention in the particular embodiment above described, it will be understood that I do not limit myself 15 to this exact construction as I may employ equivalents known to the art at the time of the filing of this application without departing from the scope of the appended claims.

20 What I claim is:

1. In a legging, the combination of a sheet of flexible material for encircling the leg of the user with one vertical edge portion overlapping the opposite edge portion, metal 25 pockets secured to the outer surface of the inner one of said edge portions adjacent the upper and lower edges of said sheet, said pockets opening towards each other, means holding said pockets in desired spaced relation, and a flexibly resilient metal bar secured to the outer one of said edge portions and extending vertically to enter and engage said pockets at its ends with the legging in place on the leg of the user, whereby 30 springing said bar outwardly away from said inner edge portion releases said bar from said pockets, said bar having shouldered portions adjacent its ends limiting the extent of engagement between its ends and said pockets.

40 2. In a legging, the combination of a sheet of flexible material for encircling the leg of the user with one vertical edge portion overlapping the opposite edge portion, horizontally disposed sheet metal strips secured to 45 the outer surface of the inner one of said edge portions adjacent its upper and lower edges, said strips each having a plurality of pockets extending therefrom, the pockets of each strip opening towards the other strip, the outer one of said edge portions having a hem along its vertical edge, a flexibly resilient metal bar in said hem and having its ends in a pocket of each strip with the legging in place on the leg of the user, whereby 50 springing said bar outwardly away from said inner edge portion releases said bar, and a reinforcing member connecting said sheet metal strips and holding them a desired distance apart.

55 3. In a legging, the combination of a sheet of flexible material for encircling the leg of the user with one vertical edge portion overlapping the opposite edge portion, horizontally disposed sheet metal strips secured to 60 the outer surface of the inner one of said

edge portions adjacent its upper and lower edges, said strips each having a plurality of pockets extending therefrom, the pockets of each strip opening towards the other strip, the outer one of said edge portions having a hem along its vertical edge and a flexibly resilient metal bar in said hem and having its ends in a pocket of each strip with the legging in place on the leg of the user, whereby springing said bar outwardly away from said inner edge portion releases said bar, said bar having shouldered portions adjacent its ends limiting the extent of engagement between its ends and said pockets.

4. In a legging, the combination of a sheet of flexible material for encircling the leg of the user with one vertical edge portion overlapping the opposite edge portion, metal pockets secured to the outer surface of the inner one of said edge portions adjacent the upper and lower edges of said sheet, said pockets opening towards each other, and a flexibly resilient metal bar secured to the outer one of said edge portions and extending vertically to enter and engage said pockets at its ends with the legging in place on the leg of the user, whereby springing said bar outwardly away from said inner edge portion releases said bar from said pockets, said bar when free from stress being curved with its ends extending away from said inner edge portion, whereby with the ends of said bar in said pockets said bar presses said outer edge portion snugly against said inner edge portion.

5. In a legging, the combination of a sheet of flexible material for encircling the leg of the user with one vertical edge portion overlapping the opposite edge portion, horizontally disposed sheet metal strips secured to the outer surface of the inner one of said edge portions adjacent its upper and lower edges, said strips each having a plurality of pockets extending therefrom, the pockets of each strip opening towards the other strip, the outer one of said edge portions having a hem along its vertical edge, and a flexibly resilient metal bar in said hem and having its ends in a pocket of each strip with the legging in place on the leg of the user, whereby springing said bar outwardly away from said inner edge portion releases said bar, said bar when free from stress being curved with its ends extending away from said inner edge portion, whereby with the ends of said bar in said pockets said bar presses said outer edge portion snugly against said inner edge portion.

6. In a legging, the combination of a sheet of flexible material for encircling the leg of the user with one vertical edge portion overlapping the opposite edge portion, a vertically disposed flexibly resilient metal bar secured to the outer one of said edge portions, and retaining devices on the inner one of said

edge portions for engaging the ends of said bar, said bar when free from stress being curved with its ends extending away from said inner edge portion, whereby with the ends of said bar engaging said retaining devices said bar presses said outer edge portion snugly against said inner edge portion.

In witness whereof, I hereunto subscribe my name this 15th day of May, A. D. 1928.
